UNITED STATES PATENT OFFICE.

BERTHOLD JAHN, OF NEW BRITAIN, CONNECTICUT, ASSIGNOR TO THE B. JAHN MANUFACTURING COMPANY, OF NEW BRITAIN, CONNECTICUT.

COIN-CONTROLLED VENDING MACHINE.

1,419,055.

Specification of Letters Patent. Patented June 6, 1922.

Application filed March 31, 1917. Serial No. 158,777.

To all whom it may concern:

Be it known that I, BERTHOLD JAHN, a citizen of the United States, residing at New Britain, in the county of Hartford and State 5 of Connecticut, have invented certain new and useful Improvements in Coin-Controlled Vending Machines, of which the following is a specification.

My invention relates to improvements in 10 coin-controlled vending machines, and the object of my improvement is simplicity and economy in construction and conveniency and efficiency in use.

In the accompanying drawing:—

15 Figure 1 is a front elevation of my improved coin-controlled vending machine.

Figure 2 is a side elevation of the same.

Figure 3 is a plan view of the same.

20 Figure 4 is a front elevation of the casing, with the cover removed, showing the interior of the casing and the mechanism operatively supported by the casing.

Figure 5 is a similar view, with the magazine in place.

25 Figure 6 is a sectional view on the line *xx* of Fig. 3.

Figure 7 is a rear elevation of the magazine.

Figure 8 is a side elevation of the same.

30 Figure 9 is a plan view of the blank for the operating lever.

Figure 10 is a plan view of the blank for the thumb piece.

Figure 11 is a plan view of the blank for 35 the latch.

Figure 12 is a fragmentary view, on an enlarged scale, of certain parts shown in Fig. 4.

My improved coin-controlled vending machine is housed in an elongated rectangular casing 10, provided with a cover 11 on the front, and is adapted to deliver goods 12 through an opening 13 in the left side wall 14, responsive to the insertion of a coin 15 in the coin-slot 16 in the top wall 17 and a downward pressure on the thumb-piece 18, the latter projecting laterally through a slot 19 in the upper part of the right side wall 20.

50 The goods 12 are supported in a column in a goods channel 21 in a magazine 22 of skeleton construction, separably mounted on the back wall 23 of the casing 10, the bottom piece of the said goods 12 resting on the magazine bottom 24, in line with an 55 opening 25 in the left side wall 27 of the

magazine, which opening 25 registers with the delivery opening 13 in the casing 10. The magazine bottom 24 has an opening 28 extending along the middle portion for the greater portion of the length thereof that 60 serves to permit the upper edge portion of the coin to engage with the bottom piece of goods for effecting the ejection of the same. The magazine 22 is provided adjacent the right side wall 29 with a division wall 30 65 in spaced relation to the said right side wall 29 so as to provide a vertical coin chute 31 that is in line with the coin slot 16, the said coin chute 31 being continuous and open at the top and bottom. The upper front portions 32 of the walls 29 and 30 of the coin chute 31 are cut away, as shown, to provide an operating space for a spring supported arm 33 that bridges the chute, which arm is normally spaced from the rear wall 34 of 75 the chute by a distance that is appreciably smaller than the diameter of the coin 15. As shown the bridge-arm 33 is in the form of a laterally directed branch of a piece of spring wire, the body portion 35 of which 80 extends along the outer side of the right wall 29 of the magazine and has the end remote from the said branch 33 secured to the said side wall 29.

The magazine 22 is provided on the rear 85 wall 36 with a plurality of off-set lugs 37, shown as three in number, for cooperating with a set of channel lugs 38 on the rear wall 23 of the casing 10, for holding the magazine in the said casing 10. 90

The ejection of the goods is effected by means of an operating lever 39 that is operatively connected to the thumb piece 18 through the medium of a cam plate 40. The lever 39 is pivotally supported from the back 95 wall 23 of the casing 10 by means of a pin 41 positioned a short distance below the upper end, leaving the upper end portion or upper arm 42 extending above the pivotal support. The said upper end portion 42 is 100 operatively housed in a cam recess 43 in the cam plate 40, the said cam plate being pivotally supported from the back wall 23 by a pin 44. The thumb piece 18 is part of a thumb piece plate 45, the body portion 46 105 of which is pivotally supported by a pin 47 and is provided with a nose 48 for cooperating with the opposed bearing edge 49 of the cam plate 40.

The lever 39 has the body portion extend- 110

ing along the front face of the back 23, being held normally to the right by a spring 50, and at the lower end, between the bottom 24 of the magazine 22 and the coin platform 51, has a forwardly extending arm 52 provided with a coin recess 53, the said recess 53 being normally positioned in registration with the lower end of the coin chute 31, to receive the coin 15 within the said coin recess 53. The lever 39 is made of a single piece of strip material of uniform width, bent to form the arm 52, the width being sufficient to provide for the slot 53 that serves as the coin recess. 10
15 The coin platform 51 mentioned is fixedly supported from the back 23 of the casing 10 and serves as a rest along which the coin 15 slides as it is pushed along by the lever 39 during the operation of ejecting the goods 20 12, and corresponds in length almost though not entirely to the length of travel of the coin. Actually there is a space between the right end of the platform 51 and the right wall 20 of the casing 10 that is filled by a 25 movable platform extension 54, which is provided for a special purpose to be described.

The said platform extension 54 is part of latch mechanism that it provided for engaging with the lower end of the lever 39 for the purpose of locking the said lever against movement away from the normal position under normal conditions and which latch mechanism is released by the weight 30 35 of the coin when dropped on the said platform extension 54, and comprises a shoulder 55 on a latch plate 56 for engaging with the said lever 39.

The latch plate 56 is pivotally mounted 40 on the back 23 by a pivotal pin 57, and the body portion extends generally horizontally along the front face of the said back, on each side of the pivotal support. The part 58 at the left of the pivotal support serves 45 as a counterweight to keep the other end, with the platform extension 54 and the shoulder 55 in the elevated position under normal conditions. When in such normal position the lower end 59 of the body portion 50 of the lever 39 is just back of the shoulder 55, and is locked thereby against lateral movement. When the coin is delivered from the chute 31 to the platform extension 54, which is just below the chute, 55 the weight of the coin trips the latch and releases the lever from engagement with the shoulder 55 and permits the free operation of the lever.

Thus the latch mechanism as described 60 prevents the operation of the lever when

there is no coin resting on the platform extension.

It will be noted as described that the delivery opening for the goods is on the left side and on the right side there is the coin 65 slot at the top and the thumb piece at the side, just below the coin slot. This combination I find to be particularly convenient in use.

It will be noted that the operative mechanism is all mounted on the casing, the cover being plain, and the goods are in a separable magazine that is slipped into place in a convenient manner.

I claim as my invention:—

1. A vending machine comprising a casing having a goods channel, a coin chute, and a goods delivery opening, a lever having a recess for holding a coin delivered from the said chute, and operative through the medium of the said coin to eject the goods from the said channel through the said opening, a platform for supporting the said coin during such movement, the said platform comprising a fixed portion for supporting the said coin during the major part of its travel, a latch device having a platform extension for receiving the coin from the said chute, and the said latch device having a shoulder that normally locks the said lever in non-operative position.

2. In a vending machine, a lever for ejecting goods from the said machine and having a recess for holding a coin, a fixed platform for supporting the said coin during the major part of its movement, and a latch device for locking the said lever normally and operative to be released from the locking position by the said coin comprising a platform portion, positioned adjacent the said fixed platform, that serves to receive and support the said coin before delivery to the said fixed platform.

3. In a coin controlled vending machine, a casing having a fixed rear wall, a goods 105 ejecting lever fulcrumed on the said wall and having a relatively short power arm, a handle device for operating the said lever projecting through one of the side walls of the said casing, and an intermediate plate 110 fulcrumed on the said rear wall, having one cam portion for cooperating with the said handle device and having a second cam portion for cooperating with the said power arm of the lever.

BERTHOLD JAHN.
